UNITED STATES PATENT OFFICE.

JOHN C. RINGE, OF STRATFORD, CONNECTICUT, ASSIGNOR TO THE SINGER MANUFACTURING COMPANY, OF ELIZABETH, NEW JERSEY, A CORPORATION OF NEW JERSEY.

TRIMMING MECHANISM FOR SEWING MACHINES.

Application filed October 7, 1924. Serial No. 742,095.

This invention relates to improvements in that class of sewing machine trimmers more particularly adapted to trim off the edge of the lower of two pieces of material during the stitching operation, and in which a knife is carried by a horizontally swinging arm. An object of the present invention is to provide a simple and effective trimmer of the class referred to, adapted to be used in connection with a sewing machine having a work-support comprising a vertically extending post.

Another object of the invention is to provide a trimming mechanism of the class referred to for a post machine, which may be readily thrown into and out of operation during the operation of the machine.

A further object of the invention is to provide an improved form of edge-guide for use in combination with a horizontally swinging trimmer in a post machine.

The improved trimmer comprises a blade-carrying arm extending laterally from the upper end of a vertical rock-shaft, disposed adjacent the work-supporting post and journaled for oscillation in bearing-brackets projecting therefrom. To actuate the trimmer-blade there is clamped upon the rock-shaft, adjacent its lower end, an arm which is releasably latched with an actuating arm pivotally mounted on the rock-shaft and having a depending fork straddling an eccentric on the usual loop-taker actuating shaft below the bed-plate of the machine. A torsion-spring surrounding the rock-shaft functions to throw the trimmer-blade into a predetermined inoperative position when the actuating arm is released from the rock-shaft.

An edge-guide for the work overlies the trimmer-blade and is adjustably secured upon an arm pivotally mounted upon the upper bearing-bracket of the rock-shaft for swinging movements about a horizontal axis into and out of operative position. The operative position of the edge-guide is determined by the engagement of its carrying arm with a limit-screw, said edge-guide being frictionally held in any position into which it may be swung.

In the accompanying drawings, Fig. 1 is a side elevation, partly in section, of a portion of a post sewing machine embodying the present improvements. Fig. 2 is a front end elevation of a part of the work-supporting post and showing the needle and presser-

bars. Fig. 3 is a top-plan view of a part of the bed and post. Fig. 4 is a sectional view substantially on the line $x-x$ of Fig. 3. Fig. 5 is a perspective view of a portion of the trimming knife.

Referring to the drawings, the sewing machine to which the present improvement has been applied includes a supporting frame or bed 1 from which rises the vertical work-supporting post 2. Journaled in the supporting frame 1 is an actuating shaft 3 which may be rotated in any usual manner. The shaft 3 carries a bevel-gear 4 in mesh with a similar gear 5 secured upon a vertical loop-taker shaft 6, journaled for rotation in suitable bearings provided within the post 2 and carrying at its upper end the usual thread-mass carrying loop-taker 7. Operatively disposed within the post 2 is a feed-bar 8 which may be actuated in any suitable and well known manner, said feed-bar carrying at its upper end a feed-dog 9 which is adapted to operate in a slot 10 provided in a throat-plate 11 secured by screws as 12 upon the upper end of the post 2. Opposed to the feed-dog is a roller-presser 13 carried by a presser-bar 14 suitably mounted in the head of the usual overhanging bracket-arm (not shown) of the machine, while adjacent to said presser-bar is disposed a needle-bar 15 carrying a needle 16. All of the described parts are well known in a sewing machine having a vertical work-supporting post and it is therefore deemed unessential to illustrate and describe the same in detail.

Referring now more particularly to the present improved trimming mechanism, the work supporting post 2 is provided at its upper end with a laterally projecting lug 17 and adjacent its lower end with a pair of lateral lugs, as 18, which lugs are formed with aligned apertures to provide bearings for a vertical trimmer-shaft 19. Above the lug 17, the trimmer-shaft 19 is provided with a head 20, upon which is secured by screws, as 21, a horizontally vibrating trimmer-blade carrier 22. Secured by screws, as 23, upon the under side of the carrier 22 is the shank 24 of a trimmer-blade having the usual depending lip 25 terminating in a cutting edge 26. The forward corner 27 of the trimmer-blade is preferably upturned to facilitate the passage thereunder of one ply of the work. The depending lip 25 of the trimmer-blade is disposed in a recess 28 pro-

vided in the throat-plate 11 by cutting away a portion thereof to form a vertical shoulder 29 with which the lip 25 has sliding contact. The blade-shank 24 may be adjustably depressed against its own resilience by a set-screw 30 threaded into the carrier 22.

In order to rock the shaft 19 to operatively vibrate the trimmer-blade, an arm 31 is fixedly clamped by a screw 32 upon said shaft 19 between the lugs 18. The arm 31 projects laterally from the shaft 19 and thence downwardly, being formed at its free end with a socketed boss 33 in which is slidingly disposed a latch-plunger 34 depressed by a spring 35 within the boss 33. The downward movement of the plunger under the action of the spring 35 is limited by the engagement of a head 36 of the plunger with the boss 33. An actuating arm 37 is mounted upon the shaft 19 for pivotal movement relatively thereto, i.e., it is loosely clamped upon said shaft by a screw 38. The free end of the arm 37 is provided with an aperture 39 adapted to receive the plunger 34 whereby in the operative position of the trimmer-blade the two arms vibrate in unison. To vibrate the actuating arm 37 it carries a depending fork 40, straddling an eccentric 41 provided upon the loop-taker actuating shaft 3 and extending through a slot 42 formed in the frame.

It is apparent from the foregoing description that when the two arms 31 and 37 are latched by the plunger 34 for unison vibration, the eccentric 41 will cause rocking movements of the vertical shaft 19 whereby the trimmer-blade is vibrated to sever the work. Means are, however, provided for at will disconnecting the trimmer-blade from its actuating mechanism and to simultaneously throw said blade into an inoperative position. To this end, a release-lever 43, 44 is pivotally mounted upon a pivot-pin 45 on the free end of the actuating arm 37, one arm 43 of said lever constituting a thumb-piece for convenient manipulation thereof and the other arm 44 being curved upwardly to enter the latch-aperture 39 and engage the lower end of the plunger 34. By depressing the arm 43 of the release-lever, the plunger 34 is lifted out of the aperture 39, whereupon a coil-spring 46 surrounding the vertical rock-shaft 19 acts to impart to said rock-shaft a greater extent of movement than its normal or operating retractive movement, thereby throwing the trimmer-blade into the inoperative position indicated by dotted lines in Fig. 3. This inoperative position of the trimmer-blade is determined by the engagement of the arm 31 with a somewhat resilient lateral ear 47 of a stop-bracket 48 secured by screws as 49 (only one of which is shown) upon a cover-plate 50. The

cover-plate 50 is secured by screws, as 51, upon the machine frame and constitutes a housing for a portion of the actuating arm 37, said cover-plate being also provided with a stop-lug 52. When it is desired to throw the trimmer-blade from an inoperative to an operative position, the arm 31 is swung rearwardly until the plunger 34 latches with the aperture 39 and to facilitate this movement the front portion of the free end of the arm 37 is formed with an incline 53 for lifting the latching plunger against the action of its spring. The latching position of the plunger is approximately determined by the lug 52.

The work-severing action of the trimmer-blade is the same as heretofore in underedge trimmers of this class and is so well known that it is not deemed necessary to herein describe the same in detail, the present invention residing more particularly in the supporting and actuating mechanism therefor as applied to a post machine. As usual, there is provided an edge-guide 54 for the upper ply of the work, which guide overlies the trimmer-blade. In the present instance, however, the shank of the edge-guide 54 is adjustably secured by screws as 55 upon an arm 56 which curves upwardly over the front edge of the blade-carrier 22 and is pivotally supported by a screw 57 threaded into the upper bearing-lug 17. A friction-washer 58 interposed between the head of the screw 57 and the arm 56 retains said arm in any position into which it may be swung, the movement of said arm into the operative position of the guide being checked by the engagement of a notch 59 in said arm with a stationary limit-screw 60.

Having thus set forth the nature of the invention, what I claim herein is—

1. In a sewing machine, the combination with a supporting-frame and a work-supporting post projecting vertically therefrom, of a trimming-blade disposed above said post, a horizontally vibrating trimmer-blade carrier, a vertical rock-shaft disposed adjacent said post from which said carrier extends laterally, and means for oscillating said rock-shaft to vibrate said trimming-blade.

2. In a sewing machine, the combination with a supporting-frame, and a work-supporting post projecting vertically therefrom, of a vertically disposed rock-shaft journaled in bearings provided by said post, a trimmer-blade carrier extending laterally from said rock-shaft, a trimmer-blade carried thereby, and means for oscillating said rock-shaft to actuate the trimmer-blade.

3. In a sewing machine, the combination with a supporting-frame, and a work-supporting post projecting vertically therefrom, of a horizontally vibrating trimmer-blade disposed above said post, a vertical trimmer-blade carrying rock-shaft journaled in

said post, a vibratory arm projecting laterally from said rock-shaft, an actuating arm pivoted coaxially with said rock-shaft, means for vibrating said actuating arm, and an 5 operative connection between said arms releasable during the operation of the machine.

4. In a sewing machine, the combination 10 with a supporting-frame, and a work-supporting post projecting vertically therefrom, of a horizontally vibrating trimmer-blade disposed above said post, a vertical trimmer-blade carrying rock-shaft, a vibratory arm projecting laterally from said rock-shaft, an actuating arm pivoted coaxially 15 with said rock-shaft, means for vibrating said actuating arm, an operative connection between said arms releasable during the operation of the machine, and a spring for 20 throwing said trimmer-blade out of operative position upon release of said connection.

5. In a sewing machine, the combination 25 with a supporting-frame, and a work-supporting post projecting vertically therefrom, of a horizontally vibrating trimmer-blade disposed above said post, a vertical trimmer-blade carrying rock-shaft, a vibratory arm projecting laterally from said rock-shaft, an 30 actuating arm pivoted coaxially with said rock-shaft, means for vibrating said actuating arm, an operative connection between said arms releasable during the operation of the machine, a coil-spring surrounding said 35 rock-shaft for throwing said trimmer-blade out of operative position upon release of said connection, and a stop for determining the inoperative position of said blade.

6. In a sewing machine having a support- 40 ing-frame, in combination, a vertically disposed rock-shaft journaled in said frame, a trimmer-blade carrier operatively connected with said rock-shaft, a vibratory arm projecting laterally from said rock-shaft for 45 movement therewith, an actuating arm, one of said arms being provided with a spring-pressed plunger and the other arm with a latching aperture for reception of said

plunger, means for releasing the plunger from its arm-latching position during the 50 operation of the machine, and means for vibrating said actuating arm.

7. In a sewing machine having a supporting-frame, in combination, a vertically disposed rock-shaft journaled in said frame, a trimmer-blade carrier fixed upon said rock-shaft, a vibratory arm projecting laterally from said rock-shaft, an actuating arm fulcrumed coaxially with said rock-shaft having a latching aperture, a spring-pressed 60 plunger provided on said vibratory arm adapted to enter said aperture to operatively connect said arms, a plunger release-lever carried by said actuating arm, and means for vibrating the actuating arm. 65

8. In a sewing machine having a supporting-frame provided with a vertical work-supporting post, in combination, a vertical rock-shaft disposed adjacent said post, a horizontally vibrating trimmer-blade carrier fixed upon said rock-shaft, a vibratory arm projecting from said rock-shaft for movement therewith, an actuating arm capable of vibratory movements independently of said rock-shaft, a latching connection between said arms to compel vibration thereof in unison, means for at will releasing said latching connection, a housing 70 for the actuating arm, and a stop-lug for said actuating arm provided upon said hous- 75 ing.

9. In a sewing machine having a supporting-frame provided with a vertical work-supporting post, in combination, a horizontally vibrating trimmer-blade disposed 85 above said post, a trimmer-blade carrier, means for actuating said carrier, an edge-guide overlying said trimmer-blade, an edge-guide carrying arm supported by said post for pivotal movement about a sub- 90 stantially horizontal axis, and means for fixedly determining the operative position of said edge-guide.

In testimony whereof, I have signed my name to this specification.

JOHN C. RINGE.
